UNITED STATES PATENT OFFICE.

CHARLES A. BLUHM, OF MICHIGAN CITY, INDIANA.

REFRIGERATOR.

SPECIFICATION forming part of Letters Patent No. 365,901, dated July 5, 1887.

Application filed November 26, 1886. Serial No. 219,891. (No model.)

To all whom it may concern:

Be it known that I, CHARLES A. BLUHM, a citizen of the United States, residing in Michigan City, in the county of La Porte and State of Indiana, have invented a new and useful Improvement in Refrigerators, of which the following is a specification.

My invention relates to refrigerators or ice-boxes.

10 In my invention the refrigerator has double walls with an air-space between. The outer or non-conducting wall is composed of two, three, or more thicknesses of boards, felt, paper, or other non-conducting material, and the inner or conducting wall is made of metal, preferably zinc or galvanized sheet-iron. The ice chamber or receptacle is arranged at the top of the refrigerator, and below this ice chamber or pan is the refrigerating-chamber, 20 in which the meat or other articles to be preserved are placed on suitable shelves. A space is left between the inner or sheet-metal wall of the refrigerator and the ends of the ice pan or chamber at both ends of the refrigerator, so as to permit free communication of air from the top of the ice-pan downward into the refrigerating-chamber. The ends or walls of the ice-pan are also provided with openings or passages for the air, and the space between 25 the ends of the ice-pan and the inner or sheet-metal wall of the refrigerator is divided by a vertical partition, preferably of sheet metal, which partition is furnished at its lower edge with an inwardly-projecting deflecting-plate, 30 which deflects the cold air centrally downward through the center or middle part of the refrigerator-chamber. By this means the cold air from the ice chamber or pan is directed downward to the refrigerating-chamber not only along the outside or walls of the same, but also centrally through its middle. The air-space between the inner sheet-metal wall of the refrigerator and the outer or non-conducting wall of the same extends at the bottom 35 as well as at the sides of the refrigerator, and the floor or bottom of this inner wall is provided with a central ventilator or opening, through which the warm or foul air from the refrigerator-chamber may escape or pass out 40 through the air-space between the inner and outer walls of the refrigerator, such air-space communicating with or leading to a ventilator 45

or opening in the top or cover of the refrigerator. The ventilator at the floor or bottom of the refrigerating-chamber is furnished with a 55 pan covering the opening in the inner wall, and the air-passages are through the holes in the vertical sides of this pan. This pan serves to catch all articles which may be spilled in the refrigerating-chamber—such as milk, for 60 example. A water-pan below the refrigerating-chamber collects the water from the ice-pan through a drip-pipe. The drip-pipe extends from the ice-pan to a separate purifying or filtering pan, also at the bottom of the refrigerator, and containing charcoal or other filtering material. This filtering-pan is furnished with an overflow-opening, through which the cold water is discharged into the water-pan. A cock or faucet is provided, 70 through which the cold water may be drawn off from time to time from the water-pan, and thus utilized for drinking or other purposes.

My invention consists in the novel devices and novel combinations of devices herein shown 75 and described, and more particularly pointed out in the claims.

In the accompanying drawings, which form a part of this specification, and in which similar letters of reference indicate like parts, 80 Figure 1 is a perspective view of a device embodying my invention. Fig. 2 is a central vertical longitudinal section. Fig. 3 is a cross-section on line 3 3 of Fig. 2, and Figs. 4 and 5 are horizontal sections on lines 4 4 and 5 5 85 of Fig. 2.

In said drawings, A represents the outer or non-conducting wall, composed of three layers of boards, a, a', and a'', and the interposed felt a''. The layers of boards are matched, 90 and the inner layer, a, extends horizontally, being nailed to the vertical posts or frame-pieces A', while the next layer, a', extends vertically. At the front and ends of the refrigerator the outer layer of boards, a'', is not 95 complete, being simply panels.

A'' are the horizontal frame-pieces. At the floor or bottom the outer wall is composed of but two layers of boards, a and a', and the felt a'', the ends of the bottom boards being 100 nailed directly to the boards a a' of the sides and ends.

B is the inner zinc or other sheet-metal wall of the refrigerator. It extends around the

vertical sides and ends and over the bottom of the refrigerator, leaving a continuous air-space, C, between the same and the outer or non-conducting wall, A, excepting in so far as such space is broken or divided by the vertical and horizontal frame-pieces A' A². These frame-pieces A' A² are, however, furnished with air passages or openings c through the same in so far as may be necessary to form a continuous air-communication from the central ventilator-opening, C', in the bottom of the inner wall, B, to the ventilator-opening C² through the outer wall at the top or cover D. The inner or zinc wall, B, is supported at the proper distance above the bottom of the outer wall, A, upon a platform, E, composed of cross frame-pieces and resting upon ledges or pieces E', nailed or otherwise secured to the outer wall, A. The central cross-pieces, E E, of this platform form a central rectangular recess or opening, and the bottom B' of the inner or sheet-metal wall is furnished with a central opening, b, conforming thereto, and a depending flange, b', surrounding such opening, said flange being turned down over the cross-pieces E E. The bottom B' is also furnished with a raised rim or fold, b², to prevent any spilled materials, water, or dirt from dripping into the water-pan F below from the refrigerating-chamber G. The opening or recess b thus formed in the bottom B' of the inner wall is closed by a drip-pan, B², having a horizontal ledge or flange, b³, which overlaps and rests upon the cross-pieces E E, whereby said pan B' is supported. The ventilator-openings C C', which constitute the means of communication between the refrigerating-chamber G and the space C between the inner and outer walls, B A, are formed in the vertical sides and ends of this pan B², so that no spilled material or articles can fall from the refrigerating-chamber into the water-pan F below. The water-pan F is supported upon cleats or cross-pieces f, resting on the floor or bottom of the outer wall, A. In the water-pan F is a second pan, F', formed by a partition, f', which is filled or partially filled with charcoal, F², or other filtering material, and the water from the ice-pan is conducted into this filtering-pan F' by the drip-pipe F³. Overflow-openings f² through the partition f' permit the water to flow into the water-pan when it reaches a certain height. The water-pan F is furnished with a faucet or cock, f³, through which the water may be drawn off from time to time and utilized for drinking and other purposes. By this means the waste ice-water from the melting ice may naturally be utilized; but being collected in a broad pan at the bottom of the refrigerator, it materially aids in maintaining a low temperature in the refrigerator itself.

H is the ice pan or chamber in the refrigerator above the refrigerating-chamber G.

K is the ice rack or platform which supports the ice. This platform is supported upon angle-irons k, extending under the same and having bent ends k', secured by screws or other-

wise to the blocks k², which are rigidly attached to the sides of the outer wall, A. A sheet-metal bottom, K', preferably of galvanized iron, having raised ribs or folds to fit over the bars of the platform, is provided to better support the ice. By this means the weight of the ice is prevented from coming upon the water-tight bottom h of the ice-pan. The sheet-metal bottom h of the ice-pan is soldered at its side edges to the side walls, B, of the refrigerator. At its ends it is secured to the end boards, h' h', of the ice-pan. The ends h' h' of the ice-pan are covered with a zinc lining, h², and the bottom h is preferably made of zinc. A vertical sheet-metal deflector or plate, L, divides the space c' between the ends of the ice-pan and the end walls, B B, of the refrigerator. This deflector is furnished with a flange, L', at its upper edge, by which it is secured to the top of the ice-pan ends h' h', and a depending inwardly-projecting flange or bent end at its lower edge to deflect the cold air inwardly and downwardly through the center of the refrigerating-chamber. The side edges of the deflector L L are soldered to the side walls, B B, of the refrigerator. The ends h' h' are furnished with openings h³ h³, for the passage of cold air from the ice-chamber into the space c² between the ends h' h' of the ice-pan and the deflectors or partitions L L, and thence downward through the center of the refrigerating-chamber. The door or cover D at the top of the refrigerator is made large enough to permit the inner or zinc shell or wall, B, of the refrigerator to be lifted bodily out through the same. A narrow bead, b⁴, preferably of wood, is secured by screws or nails to the horizontal top frame-pieces, A², of the refrigerator just at the top of the sheet-metal wall B, to cover its upper edge and make a neater finish. The screws or nails which secure this bead may preferably pass through holes in the upper edge of the wall B. To remove the wall or shell B, the bead b⁴ is first taken off. The door D is provided with hinges d, and also with chains or stops d' to hold it up when open. The outer or marginal frame-pieces, d², of the door have bevel edges, as shown, to fit the corresponding bevel edges of the frame-pieces A². The outer wall of the hinged cover D is composed of three thicknesses of boards, a, a', and a². The inner wall of the cover is made of wood. The air-space C extends between the inner and outer walls of the cover D, the same as between the inner and outer walls of the refrigerator, and the frame-pieces d² of the cover are provided with air passages or openings c, which register, when the cover is closed, with the similar openings c in the frame-pieces A² of the refrigerator. The ventilator-opening C² through the outer wall of the cover D is furnished with a ventilator of the usual construction, and consisting of a rigid plate, c², and a rotary plate or disk, c⁴, each of said plates having openings which register or do not register with each other, according as the rotary disk c⁴ is turned to open or close the

ventilator. At the front of the refrigerator a similar ventilator, C², is provided, leading into the space C between the inner and outer bottom walls of the refrigerator. This latter 5 ventilator is usually kept closed, but may be opened occasionally to dry out the space C, as the same may become slightly damp in cold weather.

10 The refrigerator-chamber G is furnished with a number of shelves or racks, g, upon which the articles to be placed in the refrigerator may be supported. These racks rest upon sheet-metal ledges g', soldered to the inner sheet-metal walls, B.

15 N is the hinged side door of the refrigerator. The outer wall is composed of three thicknesses of boards, a a' a'', and its inner wall is made of wood lined upon the inside with zinc, n. The air-space C extends between the inner and outer walls of the door, and its upper and lower frame-pieces n' are furnished with air passages or openings c, which register with the similar openings c in the frame A² of the door.

20 25 I claim—

1. The refrigerator having an outer non-conducting wall and an inner metallic or conducting wall, with a continuous or connected air-space between the same at sides, top, and bottom, said inner wall having a central ventilator-opening through the floor or bottom thereof and said outer wall having a ventilator-opening through its top or cover, said ventilator-openings communicating together through the air-space between said walls, a refrigerating-chamber, and an ice pan or chamber above said refrigerating-chamber, said ice pan or chamber having air spaces or passages between its ends and said inner metallic 30 wall of the refrigerator for passage of the cold air downward through said refrigerating-chamber toward said central ventilator-opening in the bottom of said inner wall, substantially as specified.

2. The refrigerator having an outer non-conducting wall and an inner metallic or conducting wall, with a continuous or connected air-space between the same at sides, top, and bottom, said inner wall having a central ven-

tilator-opening through the floor or bottom 50 thereof and said outer wall having a ventilator-opening through its top or cover, said ventilator-openings communicating together through the air-space between said walls, a refrigerating-chamber, and an ice pan or chamber above said refrigerating-chamber, said ice pan or chamber having air spaces or passages between its ends and said inner metallic wall of the refrigerator for passage of the cold air downward through said refrigerating-chamber 55 toward said central ventilator-opening in the bottom of said inner wall, and deflecting-plates dividing said air spaces or passages between the ends of said ice-pan and said inner wall, whereby a portion of the cold air is deflected 60 centrally downward through the refrigerating-chamber, substantially as specified.

3. The refrigerator having an outer non-conducting wall and an inner metallic or conducting wall, with a continuous or connected 70 air-space between the same at sides, top, and bottom, said inner wall having a central ventilator-opening through the floor or bottom thereof, and said outer wall having a ventilator-opening through its top or cover, said 75 ventilator-openings communicating together through the air-space between said walls, a refrigerating-chamber, and an ice pan or chamber above said refrigerating-chamber, said ice pan or chamber having air spaces or passages 80 between its ends and said inner metallic wall of the refrigerator for passage of the cold air downward through said refrigerating-chamber toward said central ventilator-opening in the bottom of said inner wall, and deflecting-plates 85 dividing said air spaces or passages between the ends of said ice-pan and said inner wall, whereby a portion of the cold air is deflected centrally downward through the refrigerating-chamber, a water-pan below said refrigerating-chamber, and a drip-pipe connecting said ice-pan and water-pan, substantially 90 as specified.
